UNITED STATES PATENT OFFICE

2,259,806

PATCH-MAKING MACHINE

Eugene Dugaw, Tacoma, Wash.

Original application June 1, 1936, Serial No. 82,716, now Patent No. 2,168,766, dated August 8, 1939. Divided and this application August 7, 1939, Serial No. 288,880

6 Claims. (Cl. 144—2)

This is a divisional application taken from the application filed June 1, 1936, Serial Number 82,716, issued Aug. 8, 1939, as Patent No. 2,168,766.

This invention relates to woodworking machines adapted to operate tools for making patches and to patches which are adapted to be applied to veneer, plywood panels, or wood boards to fill a cut-out space therein from which a pitch pocket, knot, or other defect in the wood of the panel has been removed.

Many attempts have been made to cut these patches by machinery, but the methods heretofore in use have been too slow, too inconvenient for practical use, too costly, or they have produced poor results, thus lowering the grade and salability of the manufactured product, and did not cut a patch with a beveled edge or a slivered tip suitable for use by either the hand patcher or the sheet patcher.

It is an object of my invention to provide means whereby such a cutter may be mechanically operated; wherein the cutting force is applied to the cutter as described in Patent No. 2,168,766 adjacent the cutting edge, wherein such force is applied through a knuckle joint whereby the several knives are permitted to separate at their upper ends during the cutting stroke.

It is a further object of my invention to mount the cutting tools on a head in such manner that the whole device may be slightly rotated on its axis of motion, thereby permitting the operator to adjust the position of the knives in the machine as it is being operated so that the axis of the patch from point to point shall accurately lie parallel with the grain of the wood from which the patch is being cut. A further object of my invention is to provide a feeding apparatus which is accurately adjustable, whereby the strip from which the patches are being cut is fed through the machine at such a rate in relation to the operation of the cutters, that the wastage of wood in the strip may be reduced to a minimum.

I attain these and other objects by the devices and arrangements illustrated in the drawings filed herewith.

Fig. 1 is a side elevation of the operating head of the complete machine, parts being shown in section to illustrate the construction of the mechanism for holding and driving the knives in the machine; Fig. 2 is a partial plan view thereof; Fig. 3 is a section on the line 3—3 in Fig. 1; Fig. 4 is a plan view of one end of a patch cut by the knives; Fig. 5 is a front elevation of the complete machine; Fig. 6 is a plan view thereof;

and Fig. 7 is an enlarged view of a part of the feed ratchet.

It is the further object in my invention to use the knives illustrated and described in my application filed June 1, 1936, Serial Number 82,716, issued Aug. 8, 1939, as Patent No. 2,168,766, in conjunction with the herein described machine.

Similar numerals of reference refer to similar parts throughout the several views.

The machine for cutting patches with the above-mentioned knives comprises a suitable frame 20 supporting a table 21 on which a suitable hopper 22 is formed, adapted to receive a stack of previously cut strips 23 of veneer wood such as is used in making plywood, the said strips 23 being slightly wider than the length of the patches 7 to be cut therefrom and having their grain running across the length of the strip so that the patches 7 are cut therefrom across the strip as it passes through the machine and therefore will have their grain parallel to the longitudinal axis of the patch. A motor 24 is mounted on the rear of the machine and drives an overhead shaft 25 suitably supported from the frame 20. The front end of this shaft 25 is provided with a crank-disk 26, having an undercut radian slot 27 therein, in which the crank-pin 28 may be adjustably mounted in any suitable manner in relation to the axis of the shaft 25. A connecting rod 29 extends from the crank-pin 28 and is pivotally and adjustably secured to a feed-ratchet lever 30. This ratchet lever 30 is mounted concentric with a ratchet wheel 31 and carries a plurality of separate ratchet dogs 32, 33 and 34 thereon, said dogs being mounted in such manner that only one dog at a time will operatively engage the teeth 35 of the ratchet wheel 31, thereby permitting the teeth 35 of the ratchet wheel 31 to be spaced further apart, or permitting a closer adjustment of the action of the ratchet apparatus. The ratchet wheel 31 is mounted on a shaft 36 on which the drum 37 is secured. A second parallel drum 38 is mounted on the frame 20. A feed belt 39 is mounted on the two drums 37 and 38 and is driven by the rotation of the drum 37 through the action of the ratchet mechanism. The feed belt 39 is provided with clips 40 adapted to engage and feed the lowest strip 23 from the stack of wood or veneer in the hopper 22 so that, after each operation of the cutting mechanism, hereinafter described, the strip 23 is fed forward in the machine a certain definite predetermined amount, the extent of such feed movement being controlled by the adjustment of the crank-pin 28

on the disk 26, and the adjustment of the connecting rod 29 on the ratchet lever 30.

The above mentioned motor-driven shaft 25 is provided with a crank or, as shown, an eccentric 41 by which the cutting apparatus is operated to force the knives 1 and 2 through the strip 23 to cut the patch 7 therefrom and then to draw the said knives upward to permit the strip 23 to be fed forward the said predetermined distance by means of the above ratchet mechanism. A connecting rod 42, operated by the said eccentric 41, extends downward and is connected by a knuckle 43 to the hammer-head 44. This hammer-head 44 is of general inverted U-shape, except that its lower end is circular in form and is provided with a circular flange 45 extending outward therefrom. The knife carrier is secured to the hammer-head 44 by means of the circular ring with the flange 46 engaging the upper edge of the above-described flange 45 on the hammer-head 44. Suitable ball bearings 47 may be placed between the surfaces of the said flanges 45 and 46 to permit easy rotation of the knife carrier in relation to the hammer-head 44, in order to rotate the axis of the knives carried thereby to cause them to cut a patch 7 with its major axis parallel to the grain of the strip 23 passing under the knives.

A vertically adjustable plate 48 is mounted on suitable vertical screws 49, mounted in the frame 20, and is guided by lugs 50 entering suitable grooves 51 in the frame 20. The turn-table 52 is supported by the plate 48 and is axially turnable thereon. Suitable ball bearings 53 are mounted between the plate 48 and the turn-table 52 to permit the turntable 52 to be readily turned on its vertical axis for the above described purpose. This turntable 52 carries an anvil block 54 in its axial center, said block being formed of end grain wood suitably secured in place thereon and suitably bound by the metal belt 55 or other clamping means. The turntable 52 also carries four vertical posts 56 into which are screwed vertical guide rods 57 which extend up into the ring 58 which, in turn, is mounted in a suitable annular groove 59 in the frame 20.

The two cutter carriers 60 are each mounted on two of said guide rods 57 and move vertically thereon under the action of the driving mechanism. These two knife carriers 60 are secured to opposite portions of the under side of the above-described ring 46 and each is adapted to carry one of the two knives 1 and 2 used in cutting the patch.

Each knife carrier is provided with two upper ears or lugs 61 and with two lower ears or lugs 62, said ears 61 and 62 having suitable holes therein through which the above guide rods 57 pass and by which the motion of the said carriers 60 is vertically guided.

Each knife carrier comprises a heavy rectangular metal block and has an upper central cavity 63 in which the hereinafter described spring brace is mounted to engage the upper end of the knife 1 or 2. The lower inner portion of the block 60 is cut away and its lower surface is partially closed by a plate 64 to form a rectangular horizontal transverse slot 65 adapted to receive the knife block 66. The knife block 66 and the upper surface of the slot 65 are provided with complementary lug and groove 67, whereby the said block 66 is guided to have a direct horizontal inward adjustment. The position of the said block 66 is

controlled by means of an adjusting screw 68 passing through the lower end of the carrier 60, the end of said screw 68 being provided with an inner head 69 lying in the vertical undercut groove 70 in the rear surface of the knife block 66 (Figs. 1 and 3). The adjusting screw 68 is preferably provided with a lock-nut 71. A semi-cylindrical horizontal groove is provided in the inner face of the block 66, into which the semi-cylindrical knife holder 72 rides and is free to turn in said groove and forms a hinge joint therewith. This knife holder 72 is provided with a vertical notch or depression made in its outer face and made with the same curvature as the outer face of the knife 1 or 2 (Fig. 3), said knife being suitably rigidly secured to the knife holder 72 in the said depression.

The upper ends of each knife 1 and 2 is provided with a round socket 73 secured thereto and adapted to enter the upper cavity 63 in the corresponding knife carrier 60 and to receive the end of a compression spring 74, whose force is controlled and adjusted by means of the adjusting screw 75, passing through the carrier 60 and entering the said cavity 63. The screw 75 is provided with a lock-nut 76.

A pair of spring holding cushions 77 are secured to the under side of the plate 64. These cushions 77 engage the strip 23 of veneer from which the patch is being cut, on each side of the knives 1 and 2, and hold it down on the block 54 when the knives 1 and 2 are being withdrawn upward after cutting out the patch. The said cushions 77 are, however, raised above the strip 23 when the knives are at the upper end of their stroke so that said strip may be readily fed forward under the knives the said predetermined distance while the knives are in such elevated position that the said cushions do not engage the strip 23.

It will be of course understood that the positions of the crank 28 and the eccentric 41 on the drive shaft 25 are such, relatively to each other, that the entire extent of the feed motion is accomplished during the time that the knives are raised and so that the feed is motionless during the time that the cushions 77 and the knives 1 and 2 are in contact with the strip 23.

It will also be understood that the patch cut from the strip by the downward motion of the knives 1 and 2 stays between them and is pushed upward by the successive patches being cut from the strips as they pass. The patches have their slivers 10 cut soon after they travel upward in the space between the knives, by means of the sharpened edges 11 of the notches 9. Since the space 6 increases in size towards the top of the knives the patches travel upward therein easily.

Thus it will be seen that the tool for cutting out the patch from the strip, comprises two similar curved knives which spring apart when hit with a hammer, when used as a hand tool, thereby cutting the patch with beveled edges, and when mounted in the machine, having a substantially similar movement when actuated by the machine. Also that the machine feeds the strip of veneer, from which the patches are being cut, at such an adjusted rate as to waste as little of the wood as possible. Also that the knives may be adjusted about the vertical axis while the machine is in full operation so that the grain of the patch will always extend from point to point thereof, even if the grain in the strip does not lie exactly transverse thereof for a portion of the length of the strip. Also the machine applies the cutting force through a hinged joint at a point

near the cutting edges of the knives, thus permitting them to spring apart at their upper ends against the action of the spring braces, thus approximating the effect of holding the knives by hand.

It is of course understood that many variations may be made in the details of construction of the above described machine, without departing from the spirit of my invention as outlined in the claims.

Having, therefore, described my invention what I claim and desire to secure by Letters Patent, is:

1. In a machine for cutting patches, the combination with a frame; of a vertically reciprocating hammer-head; a knife-carrier mounted on said hammer-head and rotatable thereon about a vertical axis; means for guiding said knife-carrier; a pair of complementary knives mounted on said knife-carrier and extending downward therefrom; and means for rotatably supporting said guiding means, whereby the said knife-carrier may be rotated to adjust the longitudinal axis of the patch.

2. In a machine for cutting patches, the combination with a frame; of a vertically reciprocating hammer-head; a knife-carrier mounted on said hammer-head and rotatable thereon about a vertical axis; means for guiding said knife-carrier; a pair of complementary knives mounted on said knife-carrier and extending downward therefrom; means for rotatably supporting said guiding means, whereby the said knife-carrier may be rotated to adjust the longitudinal axis of the patch; and an anvil block mounted on said rotatable supporting means and turning therewith and adapted to support the strip of veneer from which the patch is being cut.

3. In a machine for cutting patches as set forth in claim 1, wherein the connection between said hammer-head and said knife-carrier comprises an extended flat surface adapted to transmit the force of the hammer-head to the knife-carrier;

a ring flange extending from said hammer-head; and an annular flange extending from said knife-carrier and engaging the upper surface of said ring flange.

5. In a machine for cutting patches, the combination with a frame; of a vertically reciprocating hammer-head; a flanged ring rotatably mounted on said hammer-head; two knife-carriers secured to opposite points of the under side

10 of said ring and having their upper surfaces in contact with the under surface of said hammer-head; a pair of complementary knives resiliently mounted on said knife-carriers in contact with each other; and means for guiding said knife-carriers.

15 5. A machine for cutting patches as set forth in claim 4, wherein the resilient mounting of each of the knives comprises a block mounted on the lower portion of the knife carrier; a horizontal semicylindrical groove therein; a knife holder mounted in said groove and secured to the lower portion of said knife, whereby the lower end of the knife is rigidly held against relative vertical motion on the carrier but is permitted a swinging motion thereon; and a spring brace mounted between the upper portion of the knife and the knife carrier and resiliently holding the knife in contact with the complementary knife.

20 6. A machine for cutting patches as set forth in claim 4, wherein the resilient mounting of each of the knives comprises a block laterally slidably mounted on the lower portion of the knife carrier;

25 means in said knife carrier adapted to adjust said block laterally; a horizontal semicylindrical groove in said block; a knife holder in said groove and secured to the lower portion of said knife; a spring brace mounted between the upper portion of said knife and the knife carrier, and resiliently holding the knife in contact with the complementary knife.

30 40 6. A machine for cutting patches as set forth in claim 4, wherein the resilient mounting of each of the knives comprises a block laterally slidably mounted on the lower portion of the knife carrier; means in said knife carrier adapted to adjust said block laterally; a horizontal semicylindrical groove in said block; a knife holder in said groove and secured to the lower portion of said knife; a spring brace mounted between the upper portion of said knife and the knife carrier, and resiliently holding the knife in contact with the complementary knife; and means for adjusting the pressure of said spring brace.

EUGENE DUGAW.
